UNITED STATES PATENT OFFICE.

GEORGE K. DAVOL, OF SAN FRANCISCO, CALIFORNIA.

INTERNAL-COMBUSTION ENGINE.

1,202,035.

Specification of Letters Patent.

Patented Oct. 24, 1916.

Application filed November 12, 1912. Serial No. 730,883.

To all whom it may concern:

Be it known that I, GEORGE K. DAVOL, a citizen of the United States, residing in the city and county of San Francisco, in the 5 State of California, have invented a new and useful form of Internal-Combustion Engine, of which the following forms a specification.

My invention particularly relates to a 10 form of construction whereby the piston of an internal combustion engine may be sealed with water, or the sliding relation between the working cylinder and piston may be made gas tight by the introduction of water between their surfaces, the water at the 15 same time cooling the surfaces, eliminating oil lubrication of the surfaces, and introducing some water vapor into the cylinder. My invention affords a means of accomplishing these and other ends in a practical and 20 advantageous manner.

In the accompanying drawings: Figure 1 is a sectional view taken on the axis of the cylinder and piston of a vertical engine embodying my invention, and showing only the 25 upper part of the engine, the lower part embodying the crank shaft and other parts having no direct bearing on my invention, I have shown broken away. Fig. 2 is a cross-section taken at right angles to the section shown in Fig. 1 and on the line X—X in Fig. 1.

Similar parts are designated by the same reference numbers in all the drawings.

I herein show and describe my invention 35 as applied to a two-stroke cycle internal combustion engine in which fuel is injected into the cylinder at or near the point of highest compression of the air. I consider my invention particularly applicable to this 40 form of engine but it may also be applied to a four-stroke cycle engine and to internal combustion engines in which many different cycles are carried out. Such applications will be evident.

Referring to the drawings, the frame of 45 the engine comprises two side columns 1 and 2, which are joined at their upper ends. This upper end of the frame is bored to receive the working cylinder 3, which is properly fitted and secured in place. The cylinder 50 is supplied with charging and scavenging air from any suitable source through the passage 4, which communicates with the cylinder head space 5, from which it is ad-

mitted into the cylinder or working chamber through suitably actuated valves, which having no direct bearing on my invention I have not shown. In the center of the cylinder head I have shown the lower portion of the fuel valve 6. The space 7 within the 60 cylinder head represents a water jacket. The working cylinder or chamber 3 is thus held rigidly at its upper end by the frame while its lower end extends down between the side columns of the frame. These side 65 columns 1 and 2 are faced off on their inner sides to provide flat sliding surfaces or guides for a cross head 8, which reciprocates between them. Side guiding strips 9, Fig. 2, are attached to the columns and assist in 70 guiding and retaining the cross head.

A wrist pin 10 is properly held in place in the cross head in any of the usual manners and to this wrist pin the upper end of the connecting rod 11, is connected. The lower 75 end of the connecting rod is connected to the main crank of the engine in the usual manner and together with all lower parts of the engine is not shown. It is sufficient to assume the cross head 8 reciprocated by the 80 usual connections, between the guides formed by the columns 1 and 2.

To the cross head 8 is rigidly attached in a suitable manner the working piston or 85 plunger 12. This piston or plunger is of somewhat smaller diameter than that of the main bore of the cylinder or working chamber, so then when reciprocated within the cylinder it does not come in contact with the stationary or rigid walls of the cylinder 90 or working chamber at all, but allows of a clearance space between itself and the said walls.

A ring 13 is loosely carried by the cylinder and within this ring the plunger 12 reciprocates. The inside diameter of the ring is very slightly in excess of the diameter of the plunger 12, so that there may be or there may not be actual contact between the ring and the piston or plunger, as running conditions may determine. The ring 13 is solid and continuous and is not intended to clamp or grasp the plunger.

The working chamber by which I mean that portion of the part 3, which sustains the 105 pressure of the working gases, opens at its lower end into the exhaust passage or exhaust chamber 14, from which exhaust open-

ings 15, Fig. 2, on either side, lead the exhaust gases away. The ring 13 is held partly within the said working chamber and partly extending into the exhaust space and 5 is sustained in place by the screw threaded holding ring 16, against which a shoulder on the ring 13 rests and through which the thinner lower end of the ring 13 extends. It will be understood that the ring 13 is loosely 10 held and has clearance between itself and the parts which hold it to move sidewise, or to adapt itself to the position of the working piston or plunger.

The piston or plunger 12 is shown in Fig. 15 1, at the upper end of its stroke. At the lower end of the stroke the upper end of the plunger 12 does not pass entirely out of the ring 13, but it descends low enough to pass 20 or uncover the exhaust ports or openings 25 17, formed in the ring 13, which openings are shown partly by dotted line, in Fig. 1, or in section, in Fig. 2. At the lowest point of its stroke the upper end of the piston or plunger is still within that portion of the ring 13, which is below its said exhaust ports.

The walls of the lower end of the exhaust chamber 14, approach but do not come in contact with the piston or plunger 12. A 30 lower ring 18, is held loosely in the same manner in which the ring 13 is held and may or may not be in actual contact with the piston or plunger 12. This ring acts to prevent escape of exhaust gases around the 35 piston or plunger from the exhaust chamber. The lower ring 18 is sustained in the recess provided by the holding ring 19, which is secured to the walls of the exhaust chamber by any suitable means.

40 It is now seen comprehensively that the working piston or plunger 12, rigidly attached to the guided cross head 8, reciprocates within the working cylinder or chamber and the exhaust chamber without contact with their walls, and that two loosely floating rings 13 and 18 encircle the plunger 12, with or without actual contact with it but with very small clearance, and act to close the lower end of the working chamber 45 50 and the lower end of the exhaust chamber respectively. Both these rings 13 and 18 are solid and continuous and are made with an inside diameter very little in excess of the outside diameter of the plunger 12, and 55 if all parts were properly adjusted with great accuracy could act without actual contact with the plunger, but they are made floating, or loosely held to permit of their adapting themselves to any side movement 60 that the piston or plunger may make.

To seal the clearance which there may be between the ring 13 and the plunger, and between the ring and the walls of the cylinder or working chamber, against egress of the 65 working gases, water is used, which sealing

water is introduced into the working chamber between the walls of the chamber and the piston or plunger 12, in the manner I will now describe. The working piston or plunger 12 has formed in its upper end an 70 annular passage 20, from which a number of small holes 21 open into a circular groove 22 turned on the outside of the piston. A pipe 23 connects the said annular passage with a passage 24 in the cross head 8. A plunger 25, having a hole axially through it, is secured to the cross head and the said axial hole 26 communicates with the passage 24. A check valve 27 closes the lower 75 end of the axial hole 26 against passage of 80 water from the passage 24 into the hole 26, but permits the flow in the opposite direction. The plunger 25 reciprocates with the cross head 8, and moves within a pump barrel 28. The upper end of the pump barrel 85 opens into a valve chamber 29, in which a check or suction valve 30 prevents water flowing from the chamber outwardly, but permits water to be drawn from a source of supply into the chamber 29 and pump barrel 90 through the supply passage 31.

It can now be seen comprehensively that on the downward stroke of the cross head, which corresponds to the working stroke of the piston or plunger 12, the pump plunger 25 moves down within the pump barrel 28, and causes the water to be drawn into the pump barrel through the suction valve 30, the valve 27 remaining on its seat. On the return or upward stroke of the cross head 95 which corresponds to the compression stroke of the piston or plunger 12, the pump plunger 25 rises, the valve 30 closes on its seat, and water is forced through the valve 27, 100 passage 24, pipe 23, annular passage 20, and 105 out through the small holes 21. The water so forced out through the small holes during theoretically the entire upward stroke of the reciprocating parts of the engine, is 110 expelled first into the exhaust chamber 115 through the ports 17, as the plunger is first 120 in its lower position. As the plunger 12 rises and the groove 22 is covered by the ring 13, the expelled water fills the groove 22, and the grooves shown formed on the 125 inside of the ring 13, which are formed to receive this water. As the plunger 12 rises further and the groove 22 comes above the ring 13, the water is forced into the remainder of the stroke forced into the clearance space 130 between the plunger 12 and the walls of the working chamber above the ring 13. On the succeeding or downward stroke, the pressure of the gases within the working cylinder or chamber will force some of the water 125 past the ring 13, into the exhaust chamber but enough water will remain above the ring to prevent escape of the gases. When the descending working piston or plunger uncovers the exhaust ports in the ring 13, 130

the rush of the escaping gases carries the remaining water with it into the exhaust passages.

I am now able to explain that while the ring 13 as before stated is loosely held and as far as any positive and unyielding means is concerned, may or may not be in actual contact with the reciprocating piston, it is in normal operation not intended to come in actual contact with the piston or plunger, and is kept from such contact with the piston or plunger through the action of the sealing water which is, during the expansion or down stroke and during the compression or up stroke escaping through the clearance between the ring 13 and the piston or plunger. This escaping water flowing between the ring 13 and the piston acts to prevent contact between them, largely through the effect of the well-known physical action in a fluid whereby loss of static pressure results when pressure is utilized to impart velocity to the fluid. To render this clear it may in the first place be assumed that the ring 13 be separated from the piston by exactly the same clearance on all sides. The escaping water will then flow through this clearance on all sides of the piston with a uniform velocity, and the total pressure of the water between the ring 13 and the piston 12 will be uniform on all sides. If now we assume the ring 13 to be slightly displaced relative to the piston 12, so that the two are no longer exactly concentrically disposed, but that there exists a greater clearance between them on one side than on the opposite side, then the velocity of the issuing water will be greater on the side having the larger clearance than on the opposite side having smaller clearance. This is a demonstrated fact and is due to surface friction. It also follows that the pressures of the issuing water between ring and piston will be less on the side where it has the greater velocity of flow, or on the side of greater clearance. This latter effect follows from the well-known physical action above referred to, that when static pressure is utilized to produce velocity in a fluid the static pressure of that portion of the fluid to which such velocity or such increased velocity is imparted is reduced. This is very clearly demonstrated by the action of the well-known Venturi tube. This inequality of pressure of the water escaping between the ring 13 and the piston or plunger 12 will tend to move the ring sidewise and to equalize the clearance between the piston and ring on all sides, and so will tend to keep them from actual contact. The strength of this centering action, due to water escaping under high pressure, is very great. It must be realized, in order to clearly understand this action, that the same pressure of gases is applied to the water on

all sides of the piston, so that the initial pressure which forces the water through the clearance is the same on all sides. The velocity of the water, therefore, is alone proportional to the frictional resistance which it encounters in flowing through the clearance space. This frictional resistance is greater, per unit of cross-sectional area of clearance space the closer the confining surfaces are brought together. The static pressure of the water at any portion of the clearance space therefore varies inversely with its velocity and is therefore greater on the side of small clearance, if any inequality of clearance exists. This space between the ring 13, which forms part of the working cylinder, and the piston or plunger 12, is designed to be very small, but at the same time it will be realized that it should be a sensible and definite space through which there will be a rapid flow of the sealing water. I have extensively experimented with the velocity of flow of water through such small annular spaces, using clearances which varied from $1\frac{1}{2}$ thousandths of an inch to over 12 thousandths of an inch, and at present I prefer to use for a piston of, for example, 16 inches in diameter, a clearance between it and the encircling ring of less than ten thousandths of an inch. With larger diameters of piston and with long strokes where the length of the ring 13 can be relatively increased, the allowable amount of clearance could be increased, while for a smaller piston or a relatively short ring 13 the clearance would be made less.

I wish to make clear the point that, although the clearance between piston 12 and encircling ring 13 is intended to be small, still it is always a sensible and definite clearance, properly defined, in my opinion, by the term "free", and definitely provided to permit the action of the escaping water to tend to prevent actual contact between the piston and ring. I also wish to make clear that, in accordance with the statement I have hereinbefore made, that the "working chamber" or "working cylinder" of an engine consists of that part or parts which, together with the piston, sustain the pressure of the working gases; it necessarily follows that the floating ring 12 must be regarded as forming part of the working chamber, inasmuch as this ring sustains the pressure of the working gases and forms, with the piston or plunger, a chamber of variable volume, within which the useful expansion of the gases takes place. The inside surface of the ring should, therefore, properly be regarded as forming part of the walls of the working chambers. If the ring 13 be made of relatively greater length than shown in Fig. 1, this fact becomes particularly apparent.

There will be of course some leakage be-

5 between the pump plunger and the pump barrel. This leakage can by good workmanship be reduced to a very small amount which amount can be determined and allowed for. I have, however, provided to care for this leakage in the following manner: It will be seen in Fig. 1 that the pump plunger 25, extending upward from the cross head 8, extends through an opening 10 provided with a stuffing box 32, in the lower side of the exhaust chamber, also that the pump barrel 28, extending down from above, where it is secured to the frame of the engine, passes through a hole in the upper side of the exhaust chamber, so that the pump plunger and pump barrel come together or telescope with each other within the exhaust chamber 14. Any leakage between the pump plunger and barrel will 15 therefore occur within the exhaust chamber 14, and will be led or drained or carried away with the main body of the sealing water by the exhaust gases.

20 As shown in Fig. 2, a special extension 33, 25 of the exhaust chamber 14, is made to receive the pump plunger and barrel, and this extension 33, may be regarded either as a separate chamber in open connection with the exhaust chamber or passages, or as a 30 portion of the exhaust chamber. The stuffing box 32 can be replaced by any other suitable form of packing. It will also be recognized that it is immaterial whether the pump plunger be attached to the cross head 8 and the pump barrel be held stationary as 35 shown in Fig. 1, or the pump barrel be attached to the cross head and the pump plunger be held stationary as their action will be the same in either case.

40 The long cylindrical pump barrel can of course be replaced by a chamber of any form desired and a stuffing box can be used, but the form I show in Fig. 1 is the arrangement I prefer and it will of course be recognized that many equivalent arrangements for carrying out the essential ideas may be used.

45 In these specifications and in the claims which follow I use the term "working chamber" to express what is commonly known as the working cylinder of an engine, as I regard the term "working chamber" as more descriptive of a part which may or may not be of cylindrical form, although I regard and intend the two terms in this application to an engine as synonymous, and to designate that part which forms with the working piston a chamber of variable volume within which the useful expansion of the 50 working gases takes place. I regard and intend the application of either of these terms to be properly limited to that part which together with the piston sustains the pressure of the working gases. In the construction shown in Fig. 1, therefore, the "work-

55 ing cylinder" or "working chamber" terminates where it enters the exhaust chamber and the walls of the exhaust chamber do not form in a proper sense a part of the working cylinder or working chamber. I make 60 this explanation here to avoid misunderstanding of my claims.

65 I have shown and described my invention embodied in a vertical engine which is the preferred form but its application is not limited to a vertical engine and the term "substantially vertical" which occurs in the 70 claims which follow, I intend to cover a considerable deviation from a perfectly vertical position; the limiting angle to such deviation can only be determined by experience. It should also be recognized that although 75 the ring 13, in the form I show it, extending into the exhaust chamber and having exhaust ports and a portion below or beyond the exhaust ports, is my preferred form, still it could if desired be cut off at the exhaust ports so that at the bottom of the 80 stroke the piston or plunger 12 would be entirely withdrawn from the ring. If so cut 85 off it of course will be raised so that it would be wholly within the working cylinder or chamber without extension into the exhaust chamber. While such construction would 90 sacrifice certain advantages possessed by the form I show and prefer, such a modification could be adopted without departing from the essential ideas of my invention. I 95 do not limit myself to the exact constructions shown but may employ any equivalents 100 without departing from the spirit of my invention.

105 What I claim is:

1. In a substantially vertical internal combustion engine, the combination of a 110 structure comprising a working chamber and an exhaust passage, a plunger reciprocating within said structure, a ring loosely encircling said plunger and loosely held wholly or partly above said exhaust passage, said plunger being guided to move without contact with said structure above 115 said exhaust passage, and means for introducing water into said chamber above said ring.

2. In a substantially vertical internal combustion engine, the combination of a structure comprising a working chamber opening at its lower end into an exhaust passage, a plunger reciprocating within said structure, a ring loosely fitting said plunger and loosely held wholly or partly within said chamber, said plunger being guided to move without contact with said structure above 120 said exhaust passage, and means for introducing water into said chamber above said ring.

3. In an internal combustion engine, the combination of a working chamber opening at one end into an exhaust passage, a recip-

recocating plunger externally guided to move within said chamber, a loosely held ring embracing said plunger and forming a part of the walls of said chamber, and means for introducing water into said chamber between said plunger and the walls of said chamber.

4. In an internal combustion engine, the combination of a working chamber opening at one end into an exhaust passage, a reciprocating plunger guided to move within but out of contact with the upper side walls of said chamber, a solid continuous ring loosely held wholly or partly within said chamber and loosely fitting said plunger, said ring forming the lower side walls of said chamber and means for introducing water into said chamber between said piston and the walls of said chamber.

5. In an internal combustion engine, the combination of a reciprocating plunger, an exhaust passage surrounding said plunger, a working chamber opening into one side of said exhaust passage, said plunger entering said chamber but not having contact with the upper side walls of said chamber, a ring loosely held wholly or partly within said chamber and loosely fitting said plunger, said ring forming part of the side walls of said chamber, and means for introducing water into said chamber between said plunger and the walls of said chamber.

6. In an internal combustion engine, a working chamber or cylinder, a plunger reciprocating within said chamber or cylinder, there being a free clearance space between said plunger and the walls of said chamber, said plunger and a portion of said walls having limited freedom of relative lateral movement and means for introducing a rapidly moving or issuing annular flow of water through said free clearance space, for maintaining freedom from contact between said plunger and the walls of said chamber.

7. In an internal-combustion engine, a working chamber, the said working chamber comprising walls which are laterally yieldable, a plunger, reciprocating within said chamber, the said plunger being guided by means external to said chamber, means for maintaining a clearance between said walls of said chamber and the plunger, and means for introducing water into said clearance.

8. In an internal-combustion engine, a working chamber, the walls of which are partly formed by a laterally-yieldable ring, a plunger reciprocating within said chamber and guided by means external to said chamber, and means for introducing water between said plunger and the walls of said chamber.

9. In an internal combustion engine, the combination of a working chamber opening at one end into an exhaust passage, a recip-

rocating working piston or plunger guided to move within but out of contact with the walls of said chamber, the walls of said chamber comprising a ring loosely fitting said working piston or plunger, said ring having a continuous external shoulder separating a thicker end from a thinner portion, said shoulder resting upon a retaining part secured to said working chamber, the thinner portion of said ring extending through said retaining part into said exhaust passage, together with means for introducing water into the working cylinder or chamber between its walls and said piston or plunger.

10. In an internal combustion engine, the combination of an exhaust chamber, a working chamber opening into said exhaust chamber, a plunger passage opening into said exhaust chamber in line with said working chamber, a reciprocating plunger moving within said plunger passage and within said working chamber but guided to have no contact with the walls of said plunger passage or with the walls of said working chamber, two rings loosely fitting said plunger, one of said rings being loosely held wholly or partly within said working chamber, and one of said rings being loosely held wholly or partly within said plunger passage, and means for introducing water between said plunger and the walls of said working chamber.

11. In a substantially vertical internal combustion engine, the combination of a working chamber opening at its lower end into an exhaust passage, a reciprocating plunger guided to move within said working chamber without contact with its walls, said walls comprising a ring loosely held to form a continuation of the walls of said chamber and loosely fitting said plunger, said plunger being entirely withdrawn from the part of the chamber above the ring at the end of its working stroke, and means for introducing water between said plunger and the walls of said chamber.

12. In an internal combustion engine, the combination of a working chamber opening at one end into an exhaust passage, a reciprocating plunger guided to move within said working chamber without contact with its walls, said walls comprising a ring loosely held to form a part of the walls of said chamber and loosely fitting said plunger, said ring extending into said exhaust passage, and means for introducing water between said plunger and the walls of said chamber.

13. In an internal combustion engine, the combination of a working chamber opening at one end into an exhaust passage, a reciprocating plunger guided to move within said chamber without contact with its walls, said walls comprising a ring loosely held

- and extending into said exhaust passage, said ring loosely fitting said plunger and having exhaust ports or openings in it, and means for introducing water into said working chamber between said plunger and the walls of said chamber.
14. In an internal combustion engine, the combination of a working cylinder or chamber, a working piston or plunger reciprocating within said cylinder or chamber and being separated therefrom by a free annular clearance space, means for maintaining said piston free from contact with the walls of said cylinder, said piston having a water passage within the same and having an orifice or orifices opening from said water passage through the walls thereof into said clearance space, and means for forcing water through said orifice or orifices into said clearance space to seal the same.
15. In a substantially vertical internal combustion engine in which water is introduced into a clearance space between the working piston or plunger and the walls of the working cylinder, the combination of a pump plunger telescoping with a pump barrel, one of the two said pump parts being rigidly connected at its lower end to the reciprocating parts of the engine and the other of the two said pump parts being held stationary; and an exhaust passage into which the working cylinder exhausts, the two said pump parts telescoping within said exhaust passage.
16. In an internal combustion engine in which water is pumped into the working cylinder, the combination of a pump plunger telescoping within a pump barrel, and an exhaust chamber or passage into which the working cylinder exhausts, one of the two said pump parts being connected at one end to the reciprocating parts of the engine and passing through a hole in the walls of the said exhaust chamber or passage, the other being held stationary, and means to discharge the water from said pump barrel into said working cylinder.
17. In an internal combustion engine in which water is pumped into the working cylinder, the combination of a working cylinder having a chamber forming a part of, or in open connection with the exhaust passage of the engine, a pump plunger, a pump barrel, the two said pump parts telescoping with each other within said chamber and means to discharge water from said pump barrel into said working cylinder.
18. In an internal combustion engine in which water is pumped into the working cylinder, the combination of a working cylinder, a pump plunger, a pump barrel, a chamber forming part of or in open connection with the exhaust passages of the engine and having an opening in its walls provided with a stuffing box or other packing device,
- one of the two said pump parts being connected to the reciprocating parts of the engine and extending through said opening and stuffing box or other packing device, and telescoping with the other of the two said pump parts within the said chamber and means to discharge water from said pump barrel into said working cylinder.
19. In an internal combustion engine, the combination of a working cylinder having an exhaust passage, a working chamber opening at one end into said exhaust passage, a reciprocating plunger guided to move within said chamber without contact with its walls, and a loosely held ring forming a part of said walls and extending into said exhaust passage, said ring loosely fitting said plunger and having exhaust ports or openings in it.
20. In an internal combustion engine, the combination of a working chamber or cylinder opening at one end into an exhaust passage, a reciprocating plunger guided to move within said chamber without contact with its walls, a ring loosely held by the walls of said chamber and loosely fitting said plunger, the said plunger having a water passage within it and orifices opening from said water passage through the walls of the said plunger into the said working chamber or cylinder.
21. In an internal combustion engine the combination of a working chamber or cylinder opening at one end into an exhaust passage, the walls of the said chamber or cylinder having an inwardly projecting continuous flange or lip, a reciprocating plunger guided to move within said working chamber without contact with its walls and a solid continuous ring loosely resting on the said flange or lip and loosely fitting the said plunger.
22. In combination, a rigid frame, a working cylinder comprising a wall movable laterally with respect to the piston, a working piston of a diameter uniformly smaller than the diameter of said cylinder, and means to guide said piston to maintain the piston and the walls of the cylinder out of contact.
23. In combination, a rigid frame, a working cylinder on said frame, said cylinder having part of its walls rigid and another part of its walls laterally adjustable, a working piston of a diameter less than that of the walls, guiding means on said frame for guiding said piston within said cylinder and out of contact therewith, and means for maintaining the laterally adjustable walls out of contact with said piston and for preventing the passage of working gases therebetween.
24. In an internal-combustion engine, a rigid frame, a working cylinder having a rigid portion and a laterally yielding portion, a working piston of a diameter less than the diameter of the cylinder, and means

to keep said piston and said laterally yielding walls out of contact and to prevent the passage of working gases therebetween.

25. In combination a rigid frame, a working cylinder, comprising a wall relatively stationary and a wall relatively movable laterally, a working piston of a diameter uniformly smaller than the diameter of the walls of said cylinder, means on said frame 5 to guide said piston out of contact with said relatively stationary wall, and means com-

prising an annular flow of water for maintaining the piston out of contact with said laterally movable wall.

In witness whereof, I hereunto subscribe 15 my name, this 2nd day of November A. D., 1912.

GEORGE K. DAVOL.
